UNITED STATES PATENT OFFICE

CHARLES G. SMITH, OF MEDFORD, MASSACHUSETTS, ASSIGNOR TO RAYTHEON INC., OF CAMBRIDGE, MASSACHUSETTS, A CORPORATION OF MASSACHUSETTS

GASEOUS CONDUCTION DEVICE

Application filed December 21, 1925. Serial No. 76,794.

This invention relates to electronic discharge tubes generally but more particularly to gaseous discharge tubes in contradistinction to thermionic tubes, and may be used in conjunction with the inventions claimed in certain applications Serial Nos. 526,095, now Patent 1,617,179, granted February 8, 1927, 13,145, 13,146, 22,988, 55,262.

Principal objects of the invention are to increase the magnitude of discharge and to decrease the voltage drop in tubes of the character referred to, particularly with a view to adapting such tubes to comparatively heavy duty power uses.

15 In gaseous discharge tubes the voltage drop between cathode and anode, when substantial discharge is taking place, is comparatively high, being in many cases somewhat greater than the ionization or resonance voltage of the gas. According to this invention the voltage drop may be decreased far below the ionization voltage and without heating the cathode to excessive temperature. This is effected by intensely ionizing the gas 20 over a large area of cathode surface by a current produced by an electromotive force which is independent of the voltage drop between cathode and anode.

The genus of the invention is set forth in 25 the appended claims and illustrated in the accompanying drawings in which:

Fig. 1 is a vertical longitudinal section of one embodiment;

Fig. 2 is a section on line 2—2 of Fig. 1;

Fig. 3 is a section on line 3—3 of Fig. 1;

Fig. 4 is a vertical longitudinal section of another embodiment;

Fig. 5 is a section on line 5—5 of Fig. 4;

Fig. 6 is a vertical longitudinal section 40 of another embodiment; and

Fig. 7 is still another form of the invention.

The particular embodiment illustrated in Figs. 1, 2 and 3 comprises a tube 1 containing a cathode in the form of a toroid which is divided on one side to form a gap 3 between the two ends 4 and 5. At a point opposite the gap 3 a tube 6 communicates with the interior of the cathode, the tube depending to a point below the surface of a pool

of mercury 7 in the lower end of the container so that the mercury rises into the tube 6, for the purpose of heat insulation. A cylinder of insulation 8 may be provided around the lower end of the tube 6. The cathode may be mounted in the container or housing 1 in any suitable manner as for example on the lead 40. A cylinder 9 of magnetic material is mounted around the tube 6 somewhat above the level of the mercury 7, this cylinder being heated sufficiently to vaporize the mercury in the tube 6 by current induced therein as hereinafter described. The anode is in the form of a plate 10 disposed in a plane passing through the gap 3. A magnetic coil 11 surrounds the tube preferably in the horizontal plane of the toroidal cathode, for the purpose of producing induction currents in the gas within the cathode and also in the cylinder 9, as hereinafter described. The gas within the tube is preferably mercury vapor at a pressure of the order of .01 mm., although different gases may be employed either singly or in mixture.

By passing current of high frequency (for example 10^6 cycles per sec.) through coil 11, induced current is caused to flow around the toroid in the gas contained within the toroid, eddy currents in the toroid itself being restricted by the gap 3. With an induced current of sufficient magnitude the gas within the toroid and across the gap 3 may be ionized intensely. For this purpose the current in coil 11 preferably has an electromotive force per turn of more than the ionization voltage of the gas (or vapor) within the toroid. The induced current in the gas within the toroid should be quite large and for most purposes should be several amperes. This current furnishes a copious supply of ions inside the cathode. With this state of ionization, current between the cathode and anode may be maintained with a very low voltage drop between the cathode and anode, although somewhat higher potential difference between cathode and anode may be required to start the discharge.

From the foregoing it will be evident that the low voltage drop between cathode and anode results from the intense ionization

produced inside the hollow cathode and across the gap 3 by the high frequency current which is independent of the voltage drop between cathode and anode. The discharge between the cathode and anode is spread out over a large area inside the hollow cathode and consequently local heating of the cathode, which often leads to its destruction, is avoided. Moreover, the total losses in the tube are much lower than in the ordinary tube. Furthermore the very low voltage drop between cathode and anode throughout the range of operation of the tube permits the device, when used as a rectifier, to be operated in parallel with similar tubes without employing series reactances to effect a proper division of load, or at least only small reactances, owing to the fact that this tube has a rising current-voltage characteristic.

The form of the invention illustrated in Figs. 4 and 5 comprises a hollow cathode 12 in the form of a cup having a discharge opening 13 in its lower end and having its upper end open. The anode 14 is located in the bottom of the tube and the opposing surfaces of the two electrodes are preferably placed sufficiently close to each other (for example $\frac{1}{16}$ inch apart) to prevent substantial ionization in the gap therebetween as a result of electrons passing directly across the space, it being understood that the discharge passes between the interior of the hollow cathode and the anode through the opening 13. A ring 15 of magnetic material is mounted within the hollow cathode upon the lead 16 and current is induced in this ring by high frequency current in the coil 16 which is coaxial with the ring and the cathode. The cathode is preferably slit at intervals as illustrated at 17 to restrict eddy currents therein and the cathode is preferably formed of non-magnetic material so as not to shield the ring 15. The cathode preferably fits within the glass tube with a very small clearance and may be mounted in any suitable way, as for example, upon leads 18. In this form of tube the gas is preferably inert monatomic gas such as argon, neon or helium.

The tube illustrated in Figs. 4 and 5 is preferably operated as follows: The ring 15 is heated with eddy currents induced by coil 16 to a sufficient temperature to emit electrons for starting purposes and inasmuch as its primary function is for starting the main discharge between cathode and anode, it is preferably connected to the source of current through a resistance 19 so that only a small amount of current can pass between it and the anode after the tube is in operation. The ring 15 is made sufficiently small so that eddy currents are produced in the gas within the hollow cathode as well as in the body of the ring, whereby the gas adjacent the inner surface of the cathode may be ionized in-

tensely with the attendant advantages described in connection with the first embodiment. Indeed in this form the entire interior of the cathode is ionized by the eddy currents induced therein by the high frequency current in coil 16.

The embodiment illustrated in Fig. 6 comprises a hollow cathode 21 having a discharge opening 22 in its upper end and having at its lower end a tube 23 depending into a pool 24 of mercury 24. The anodes 25 and 26 are presented to the interior of the hollow cathode through the opening 22. Surrounding the cathode is a cylindrical shield 27 which is mounted on the tube 23 at 28 and has an opening in the path of the discharge between the interior of the cathode and anodes. 29 indicates the high frequency coil such as above described. In this form the cathode is made of a suitable conducting material and the shield 27 is non-magnetic and vertically slotted at intervals so that eddy currents may be induced in the cathode to heat it to incandescence. The shield 27 serves to restrict the radiation of heat from the cathode thereby to maintain the cathode at incandescence with less loss by radiation.

In operating a tube such as illustrated in Fig. 6 the high temperature of the cathode partially ionizes the vapor inside the cathode thereby rendering the gas conducting. The high frequency coil 29 can then more readily induce eddy currents in the gas within the cathode thereby heating the gas still hotter and increasing the state of ionization. Consequently in this case the voltage drop per electron mean free path in the eddy currents does not need to be as high as the ionization voltage. It will be understood that this double anode construction may be used for various purposes such as full rectification of alternating current, in which case the discharge passes alternately between the anodes and the interior of the cathode. Obviously two anodes could be employed in either of the other embodiments herein disclosed.

The tube illustrated in Fig. 7 comprises a plate anode 31 and a cathode in the form of a coiled conductor having one turn 32 in the lower end of the tube and one or more turns 33 in the region of the anode, the ends of the upper and lower turns being connected at 34 and 35 to form an endless conductor. The high frequency magnetic coil 36 surrounds the tube in the region of the lower turn of the cathode and induces current in said cathode and induces current in said lower turn. This induced current flows through the connecting portions 34 and 35 and thence through the upper turn 33, the current in the upper turn being sufficient to ionize the gas within the upper turns, either by virtue of eddy currents set up in the gas within the upper turn or by heat radiation from the upper turn or both. Shields 37 may be

mounted on the upper turn in radial planes to obstruct eddy currents in the gas around the upper turn 33 in order to localize the eddy currents in the gas within the upper turn. A shield 38, preferably though not necessarily of insulating material, may also be arranged to extend diametrically across the lower end of the tube to obstruct eddy currents in the gas in the region of the lower turn 32. The cathode may be supported in any suitable way as upon the shield 38.

From the foregoing it will be evident that each illustrated embodiment of the invention comprises means for producing intense ionization in the region of the active surface of the cathode independently of the potential difference between cathode and anode. As illustrated this ionization is preferably produced by a high frequency coil having its axis extending through the region of the source of electronic discharge (in the region of the cathode), the coil constituting induction means for inducing current in a closed orbit in the region of the source of discharge. While the induced currents are preferably in the gas, adjacent the acting surface of the cathode, they may be induced in a metallic ring or cylinder as illustrated in Figs. 4, 5, 6 and 7.

40 I claim:

1. A gaseous discharge device comprising a sealed container, a hollow cathode having a restricted discharge opening and adapted to emit electrons from its interior surface, an anode in spaced relation to said cathode, an auxiliary cathode within said hollow cathode and connected to said hollow cathode, means for inducing eddy currents in said auxiliary cathode, and means for preventing eddy currents in said hollow cathode.

2. A space current device comprising an envelope containing a gas, a cathode and an anode spaced from each other within said envelope, means adjacent said cathode enclosing, adjacent the surface of the cathode, a body of gas constituting paths for inducing therein voltages adapted to produce a discharge along said paths in said gas, and high frequency inducing means for inducing in said gas paths a voltage to produce a discharge in said paths for ionizing the enclosed gas to provide electric carriers for maintaining a discharge between said cathode and said anode.

3. A space current device comprising an envelope containing a gas, an anode in said envelope, a cathode in said envelope constituting a hollow chamber having an interior electron-emitting surface, said chamber enclosing a body of gas constituting inducing paths for inducing therein voltages adapted to produce a discharge in said body of gas along said paths, and high frequency inducing means for inducing in said gas paths a

voltage for producing a discharge along said paths and ionizing the gas therein to provide electric carriers for maintaining a discharge between said cathode and said anode.

Signed by me at Boston, Massachusetts, 70 this tenth day of December, 1925.

CHARLES G. SMITH.
